(57) **CLAIM**

The ornamental design for a dual pole towing arm, as shown and described.

DESCRIPTION

FIG. 1 provides a perspective view of the dual pole towing arm.

FIG. 2 provides a front view of the dual pole towing arm with the handle rotated.

FIG. 3 provides a rear view of the dual pole towing arm with the handle aligned.

FIG. 4 provides a right side view of the dual pole towing arm.

FIG. 5 provides a left side view of the dual pole towing arm.
FIG. 6 provides a bottom view of the dual pole towing arm; and,

FIG. 7 provides a top view of the dual pole towing arm.
The broken lines showing the towing handle and the extensions are only for illustrative purposes to show the environment of the invention and form no part of the invention.
